INJECTOR MOUNTING

Harry A. Hoke, Altoona, Pa., assignor to The Pennsylvania Railroad Company, Philadelphia, Pa., a corporation of Pennsylvania

Application March 27, 1942, Serial No. 436,428

8 Claims. (Cl. 105—37)

This invention relates to the application of feed-water injectors to boilers, tanks, and so forth; while it has reference, more particularly, to the mounting of such devices on locomotives. The application of non-lifting injectors to locomotives and the delivery of water thereby to the boiler of the newer type locomotives has presented many difficulties, the main disadvantage being incidental to the limited space and increased lateral movement afforded the rear end of the locomotive relative to the tender. It is also essential that the injector maintain a fixed relation with respect to the back end of the locomotive boiler, and such relation must not vary with the heat expansion of said boiler, as any deviation from such location of the injector results, within a short time, in failure of or trouble with the steam and water pipes. Still further, incidental to the more modern location of the locomotive trailer truck frame and the steam exhaust pipes to the "booster," the injector can not be supported by a bracket attached directly to the boiler mud-ring.

The fundamental object of the present invention is to overcome the noted disadvantages, in a simple and effective manner, by a novel means of supporting the injector so that the fore and aft movement of the boiler relative to the locomotive main frame, incidental to expansion and contraction is reciprocally neutralized so far as the injector is concerned, without any lateral motion or strain being imparted to the associated steam and water pipes, whereby failure of or trouble with said pipes is compensatively safeguarded.

With the stated object, and incidental advantages in view, this invention essentially consists in the novel features of construction and combinations of parts as set forth more particularly in the concluding claims, while a preferred embodiment of said invention is hereinafter explained with reference to the drawings which accompany and form a part of this specification, and wherein like characters of reference designate corresponding parts in all the views.

In the drawings:

Fig. 1 is a broken side elevation of the left-hand rear end portion of a locomotive preferably having a non-lifting injector applied thereto in accordance with this invention, parts being shown in section for better illustration of important details.

Fig. 2 is an end view of the same, or looking from the right of the preceding figure towards the left-hand thereof.

Fig. 3 is a top plan view; and,

Fig. 4 is a detail section on the plane designated IV—IV in Fig. 1.

In describing the embodiment of the invention, exemplified by the above captioned figures, specific terms will be employed for the sake of clarity, but it is to be understood the scope of said invention is not thereby limited; each such term being intended to embrace all equivalents which perform the same function for an analogous purpose.

As illustrated in the drawings, the rear end of a locomotive cab is comprehensively designated by the numeral 5; 6 indicates a fragmentary portion of the tender; 7 a part of the conventional stoker connection; 8 the trailer-truck frame; 9 the associated wheels; 10 the boiler rear slideable-pad; and 11 the locomotive frame cross-tie: all of said parts being referred to merely by way of providing appropriate background in explaining the present inventive subject-matter.

In the more recent type of heavy-duty locomotive, and in accordance with this invention, the feed-water injector 12 is mounted with assurance that it will not move longitudinally in respect to the locomotive boiler, by aid of a slideable bracket 13, preferably of angular formation. This bracket 13 is, conveniently, composed of lapping-related components 14, 15, the former 14 of which serves as a reinforce for the latter 15, while said components are rigidly secured together, against relative shifting, and are provided with an oil hole 15' for lubricating purposes, Fig. 4. The component 15 embodies a vertical leg 16, for rigid attachment thereto of the non-lifting injector 12, a horizontal portion 17 overlying the adjoining part of the component 14, and an obliquely-related or upwardly-inclined extension 18 having the free end bifurcated and provided with loops or eye-sections 19, for hinge-like connection or articulation by an appropriate element 20 to an apertured projection 21 from the boiler aligned rear pad 10 which is slideable longitudinally with said boiler, in accordance with known practice. This connection of the parts 19, 21, it is to be noted, always ensures the injector 12 being maintained in the desired location relative to the locomotive boiler back-end, without any possibility of variation or change from such location, for a reason hereinafter again referred to.

The bracket 13 is slidably mounted to accommodate the fore-and-aft motion due to boiler expansion and contraction, relative to the locomotive frame, by means of an inverted channel-like clamp-device 22, having an associated bearer element 23, and it is held in place by securing

means 24 on the top of the locomotive frame cross-tie 11; while the parts 22, 23 may be permanently rigidified by welds 25, in an obvious manner.

From the foregoing it will be apparent that by forming the clamp-device 22, as shown, and by affording the angle-bracket 13 slidable guidance, intermediate the bearer element 23 and the channel 26 of said device, the angle-bracket 13 is restrained from side or lateral motion, while said bracket being anchored against longitudinal shifting by the element 20 to the boiler pad 10, the injector 12 always maintains its fixed location relative to the back-end of the boiler 27, under thermal expansion and contraction of the latter. In other words, the mounting bracket 13 in no way affects the proper location of the injector 12; while it accommodates the fore-and-aft motion induced by thermal expansion and contraction of the boiler 27, whereby a simple and effective means is provided which positively prevents "failure" or causes disruption of the locomotive steam supply pipe 28, or the water hose 29, as well as the associated water supply connections.

Having thus described my invention, I claim:

1. In a steam generator, a rigid support, bearer-means for the generator movable relative to said support, an injector for supplying feed-water to the generator, a mounting for the injector slidable relative to the rigid support, and means articulating the mounting to the bearer-means for movement with the latter incidental to expansion and contraction of the generator.

2. In a steam generator, a rigid support, bearer-means for the generator movable relative to said support, an injector for supplying feed-water to the generator, a mounting for the injector slidable relative to the rigid support, said mounting serving to maintain the injector in fixed location relative to the generator, and means articulating the mounting to the bearer-means for concurrent movement with the latter incidental to thermal expansion and contraction of the generator.

3. In a steam locomotive, a frame including a cross-tie, a boiler with supporting pads cooperative with said frame and shiftable longitudinally of the latter, an injector for supplying feed-water to the boiler, a mounting for the injector slidable relative to the cross-tie, said mounting serving to maintain the injector in fixed location relative to the rear end of the boiler, and means articulating the forward portion of the mounting to the proximate boiler supporting pad, whereby said mounting is movable longitudinally in respect to the frame concurrent with thermal expansion and contraction of the boiler.

4. An injector support for steam generators comprising an angle-bracket, one leg whereof af-

fords attachment for the injector and the other leg provides the support, means for shiftably guiding the supporting leg relative to a stationary base, and means at the free end of the supporting leg for articulation to a thermal-influenced bearer part of the generator.

5. A mounting for the injector and connected water-feed and steam-supply pipes of locomotive boilers comprising an angle-bracket, one leg whereof affords attachment for the injector and the other leg forms the supporting portion of the bracket, means affording slidable guidance for the bracket supporting portion relative to a cross-tie of locomotive frame, and means at the free end of said supporting portion articulating the latter to the boiler rear end whereby thermal expansion and contraction of said boiler can not produce imperfection in or fracture of the connected water-feed and steam supply pipes.

10 6. A mounting for the non-lifting injector of steam locomotives including a boiler with bearer pads shiftable longitudinally of the locomotive frame under thermal influence, said mounting being securable to the locomotive frame and consisting of an angle-bracket having one leg vertically-disposed and affording attachment for the injector, and the other leg being horizontal and providing support therefor; guide means for the bracket supporting leg and restricting its movement to the longitudinal in respect to the locomotive frame; and fulcrum means at the free end of the bracket supporting leg for articulation to the rearmost bearer pad of the boiler, whereby expansion and contraction of said boiler does not affect the location of the injector relative to the boiler rear end.

15 7. A mounting for non-lifting injectors, in accordance with claim 6, wherein the angle-bracket comprises inner and outer lappingly-related and rigidly united components, the inner component serving as a reinforce for the outer component; said outer component embodying a vertical leg, a horizontal portion overlying the confronting part of the reinforce; and said horizontal portion having an inclined extension with its free end looped for hinge-connection to an apertured projection on the rearmost bearer pad of the locomotive boiler.

20 8. A mounting for non-lifting injectors, in accordance with claim 6, wherein the guide means for the angle-bracket supporting leg is in the form of a clamp device, said device comprising an inverted channel component effective to restrain the bracket against lateral movement while permitting it to shift in a longitudinal direction with respect to the locomotive frame; an associated bearer element; and means whereby the device is rigidly securable to the locomotive frame rear end.
